(57) **CLAIM**

The ornamental design for a portable generator frame, as shown and described.

DESCRIPTION

FIG. 1 is a top perspective view of a portable generator frame according to the present invention holding a portable generator;

FIG. 2 is a top perspective view of the portable generator frame of FIG. 1 without the portable generator;

FIG. 3 is a front view of the portable generator frame of FIG. 2;

FIG. 4 is a back view of the portable generator frame of FIG. 2;

FIG. 5 is a first side view of the portable generator frame of FIG. 2;

FIG. 6 is a second side view of the portable generator frame of FIG. 2;

FIG. 7 is a top view of the portable generator frame of FIG. 2; and,

FIG. 8 is a bottom view of the portable generator frame of FIG. 2.

The features shown in broken lines in the drawing depict environmental subject matter only and form no part of the claimed design.

1 Claim, 8 Drawing Sheets
